UNITED STATES PATENT OFFICE.

LARS J. LINDBECK, OF BISHOP HILL, ILLINOIS.

MANGLE.

SPECIFICATION forming part of Letters Patent No. 660,301, dated October 23, 1900.

Application filed June 1, 1899. Serial No. 719,029. (No model.)

To all whom it may concern:

Be it known that I, LARS J. LINDBECK, a citizen of the United States, residing at Bishop Hill, in the county of Henry, State of Illinois, 5 have invented certain new and useful Improvements in Mangles; and I do hereby declare the following to be a full, clear, and exact description of the invention, such as will enable others skilled in the art to which it applies to make and use the same.

My invention relates to mangles, and has for one object to provide a device of this nature which will be simple and cheap of construction, easy and efficient in its operation, 15 and which, moreover, when not in use will have an ornamental appearance.

A further object of my invention is to provide a readily-operated tension device for the rolls of the mangle and means for operating 20 the rolls.

In the drawings forming a portion of this specification, and in which like letters of reference indicate similar parts in the several views, Figure 1 is a front view of my mangle 25 when closed and showing the ornamental appearance thereof. Fig. 2 is a front view of my mangle with the front open and ready for operation. Fig. 3 is a section on line 3 3 of Fig. 2. Fig. 4 is a section on line 4 4 of Fig. 30 2. Fig. 5 is a detail section taken through the shaft M and showing its cam and its yieldable connection therewith.

Referring now to the drawings, in operating in accordance with my invention I form a 35 casing comprising a back a, sides b and c, top d, and bottom e, the front comprising an upper hinged lid f, hinged to a horizontal partition g in the casing and adapted to inclose a mangle-compartment, there being a lower 40 portion below said partition having drawers h for any desired purpose.

It will be noted that the sides b and c at their upper portions, which are engaged by the lid f, are sloped backwardly from the bottom of the lid to the top of the casing, giving the casing when closed more of the appearance of a desk.

Within the compartment, above the partition g and to the inner faces of the sides of 45 the casing, are secured guide-plates b' and c', the guide-plate b' (shown in detail in Fig. 4 of the drawings) consisting of a metal plate

having outwardly-directed parallel flanges at its upper and lower edges, the lower flange d' being continuous from end to end of the 55 plate, while the upper flange e' extends from the front end of the plate to a point in advance of the rear end, resulting in the formation of an entering-way f', leading into the inclosure of the flanges. A front flange g' is 60 also formed upon the front end of the plate and a rear flange h' is formed at the rear edge of the plate, said front and rear flanges projecting in the same direction with the upper and lower flanges. The guide-plate c' is similar to the guide-plate b' and is separated from the side c of the casing by an interspace i, as shown.

Journaled in bearings formed in the plates b' and c' are the trunnions k and l of a roller 70 m, which roller has a sheet of fabric n secured thereto by means of tacks or other form of fastening means along one edge of the sheet. This sheet is substantially the width of the roll and the secured edge thereof lies 75 longitudinally of the roller.

The trunnion l of the roller m passes through the plate c' and into the interspace i, within which interspace and upon said trunnion is arranged a pinion o, meshing with a second 80 and larger pinion p upon a shaft r, journaled in the side of the casing and having at its outer end a crank t, through the medium of which its shaft may be rotated to rotate the roller m.

Slidably arranged between the upper and lower flanges of each plate b' and c' is a bearing-block B and C, respectively, which blocks are adapted to move toward and away from the trunnions of the roller m. Each of the 90 bearing-blocks has a downwardly and rearwardly directed bearing-slot D, which when the blocks are at the limit of their rearward movement are in alinement with the entering-ways f', permitting the insertion of the 95 trunnions E and F of an adjustable roller H, adapted to be carried toward and away from the roller m as said bearing-blocks are reciprocated, and thus exert pressure upon or release any body entered between the adjacent surfaces of the rollers.

In order to move the bearing-blocks forwardly, and therewith the roller H, I arrange a cross-bar I, whose ends project into the in-

closure of the inwardly-directed flanges of the plates b' and c' and engage the bearing-blocks, as shown in Fig. 3 of the drawings. A second horizontal partition L and a bar K are mounted between the partition g and the top of the casing, and this bar K and the partition g have bearings in which is mounted an oscillatory shaft M, having an eccentric N fixed thereto or formed integral therewith and adapted to engage the cross-bar I and press it forwardly as its shaft is rotated in one direction and to release the cross-bar when its shaft is rotated in the opposite direction.

In order to oscillate the shaft M, I mount loosely thereon an operating-lever O, connection being made between said lever and shaft through the medium of a spring-strap P, one end of which is connected with the lever and the other end of which is passed through a diametrical perforation in the shaft. Thus is formed a yieldable connection between the shaft and its operating-lever, and as a result a yieldable pressure of the roller H against the roller m.

In order to hold the lever O in its adjusted positions to maintain pressure between the two rolls or to hold them at any desired distance apart, I form upon the bar K a notched segment R, adapted to be engaged by a projecting portion S upon the lever O.

The space above the partition L is divided to receive sliding drawers and also to form pigeonholes, as shown, or may be otherwise arranged, as may be desired.

In the operation of my invention the fabric n is drawn outwardly from the roller m to lie upon the inner surface of the lid f, which is brought to lie in a horizontal position, as shown in Figs. 2 and 3 of the drawings. The article to be mangled is then laid upon the cloth or fabric and the crank t is operated, with the result that the roller m is rotated. At the same time the lever O is operated to move the roller H forwardly and into engagement with the said fabric, exerting pressure upon said fabric and upon the material carried thereby. After the article has passed between the rollers the rotation of the rollers is reversed and the article removed from the fabric, folded, if desired, and again passed between the rollers in a similar manner. When the operation is completed, the lever O is disengaged from its

holding-segment and the roller H allowed to return. This return may be assured or assisted by means of helical springs T and U, arranged between the forward edges of the bearing-blocks and stops V on the inner faces of the plates.

It will be readily understood that I may vary the specific construction and arrangement herein shown and described, that I may use whatever material may prove advisable for the different elements of my invention, and that I may equip the casing outside of the mangle-compartment as desired without departing from the spirit of my invention.

Having thus described my invention, what I claim is—

1. A mangle comprising a roller mounted in stationary bearings, journal-blocks, a roller mounted in the journal-blocks, said journal-blocks being adapted for reciprocation to move the second roller toward and away from the first roller, a cross-bar engaged with the journal-blocks, a shaft adjacent to the cross-bar, an eccentric upon the shaft and adapted to engage the cross-bar to move it to shift the journal-blocks, a lever mounted loosely on the shaft of the eccentric, and a spring having one end connected with the lever and the other end connected with the shaft of the eccentric to form a yielding connection therewith.

2. A mangle comprising a roller mounted in stationary bearings, journal-blocks mounted for reciprocation with respect to the roller, a second roller mounted in the journal-blocks, a cross-bar engaging said blocks, a shaft journaled adjacent to the cross-bar, an eccentric upon the shaft and adapted to engage the cross-bar to move the journal-blocks, a lever mounted loosely on the said shaft, a spring connected at one end with the lever and at the opposite end with the shaft to form a yielding connection therebetween, and means for holding the lever at different points of its movement.

In testimony whereof I affix my signature in presence of two witnesses.

LARS J. LINDBECK.
